UNITED STATES PATENT OFFICE.

CHARLES W. BECK, OF ROCKVILLE CENTER, NEW YORK, ASSIGNOR, BY MESNE ASSIGNMENTS, TO MICHIGAN MOTOR SPECIALTIES COMPANY, OF DETROIT, MICHIGAN, A CORPORATION OF MICHIGAN.

TERMINAL CONNECTOR.

1,114,719.

Specification of Letters Patent.

Patented Oct. 27, 1914.

Application filed October 19, 1911. Serial No. 655,451.

To all whom it may concern:

Be it known that I, CHARLES W. BECK, a citizen of the United States, and resident of Rockville Center, county of Nassau, and 5 State of New York, have invented certain new and useful Improvements in Terminal Connectors, of which the following is a specification.

This invention relates to a simple and convenient means for connecting a terminal wire to a spark plug of an internal combustion engine, and its main object is to provide a very simple device for this purpose which may be readily and, therefore, cheaply constructed and which will be efficient in operation.

Another object of the invention is to so construct the device that the terminal wire may be readily and quickly detached from 20 the spark plug connecting means, the separable elements being inclosed within an insulating sleeve which extends over the insulated part of the terminal wire for a suitable distance, said insulating sleeve forming 25 a means by which the device may be safely handled and also forming an inclosed chamber within which any spark occasioned by the separation of the two members of the connector will be protected from surrounding 30 gasoline fumes.

In the drawings, Figure 1 is a side elevation of the connector applied to the terminal post of a spark plug; Fig. 2 a longitudinal sectional view of the connector; Fig. 3 a 35 detail view of the blank from which the terminal post engaging clip is formed; Fig. 4 a plan view of said clip after it is bent up from the blank and before it is secured to the main body of the connector; Fig. 5 a 40 plan view of the post engaging clip and the attached terminal socket; and Fig. 6 a longitudinal sectional view showing a slightly different form of spark plug terminal engaging means.

Referring to the various parts by numerals, 1 designates a portion of a spark plug for an internal combustion engine and 2 the post terminal thereof. It is manifest that the spark plug and the post terminal may be 50 of any suitable construction. On the end of the terminal wire 3 is secured a socket plug 4 by means of a screw 5. This socket plug is preferably hollow and the screw 5 passes through one closed end thereof into the terminal wire, said screw forming an efficient 55

electrical connection between the wire and the plug. This plug is formed with an external annular groove 6 at a suitable distance from the radial end flange 7 of said plug. This plug is adapted to fit snugly 60 within a split socket 8, said socket being formed with an inwardly extending projection 9 adapted to fit in the groove 6 of the plug 4 when the said socket and plug are brought into engagement with each other. 65 These two members may, therefore, be separated by suitable force supplied to the terminal wire.

The socket near its outer end is formed with a radial flange 10 and adjacent said 70 flange it is externally screw-threaded as at 11. Engaging said screw-threads and abutting against the flange 10 is a long sleeve 12 of insulating material, said sleeve normally inclosing the socket and plug and a considerable portion of the attached terminal wire. This sleeve interiorly is of substantially the same diameter as the insulation on the terminal wire so that it fits snugly over said insulation, as shown clearly in Fig. 2, and 80 surrounds and protects the socket and plug members. It is, therefore, manifest that this insulating sleeve provides a safe means by which the terminal connector may be manipulated and also completely incloses the separable members of the connector so that should a spark occur when said two members are detached or separated while the connector is attached to a spark plug, said spark will be within an inclosed chamber and thoroughly protected and shielded from any 85 gasoline fumes which may be around the spark plug.

To connect the socket member with the post terminal of a spark plug I provide a 95 post terminal receiving means secured to the closed end of said socket. This device is preferably a yielding gripping means 13 which may be quickly attached and detached from said terminal post. I preferably form 100 this gripping means from a sheet metal blank, shown clearly in Fig. 3. This blank consists of the main body portion 14, said body portion being provided near its ends with the lateral extensions 15 and with the 105 end parts 16. The end parts 16 are each pressed to form a semi-cylindrical post terminal gripping member 17. The main body part of the blank is bent midway its ends to bring the two parts of said blank together, 110

as shown clearly in Fig. 4. The lateral extensions 15 are then bent perpendicular to the main body of the blank to form the bracing lugs 18, as is also shown clearly in Fig. 4. The closed end of the socket 8 is slotted and the doubled-over portion of the main body of the blank is passed inwardly through said slot and the edges 19 of the lugs 18 are brought to bear squarely against the outer closed end of the socket, as shown clearly in Figs. 2 and 5. The folded body of the blank within the socket is then bent over and forced against the inner side of the closed end of the socket, as shown clearly in Fig. 2, thereby forming a head 20, in the nature of a rivet head within the socket and securely and rigidly locking the post terminal receiving means to the socket piece. It is manifest that a receiving means constructed as described will have sufficient resiliency in the clamping or gripping jaws 19 to insure a substantial frictional contact or grip between the said jaws and the post terminal; and the reinforcing or supporting lugs 18 will serve to strengthen said gripping means and prevent the jaws being bent laterally and broken.

It is manifest that when a terminal connector constructed as herein described is attached to the post terminal of a spark plug it may be readily detached therefrom by disconnecting the gripping means from the terminal, or if desired the terminal wire may be quickly disconnected from the socket by drawing the plug outwardly from the socket, leaving the socket and the gripping means connected to the spark plug terminal.

In Fig. 6 I have shown a hook connecting device 21 in place of the resilient gripping jaws illustrated in the other views.

Having thus fully described my invention, what I claim as new and desire to secure by Letters Patent, is:

1. A terminal connector comprising a tubular socket closed at its outer end and open at its inner end, a plug adapted to snap into the open inner end of said socket, means for connecting said plug to a terminal wire, an insulating and protecting sleeve carried by the socket and inclosing the same and extending over the connected plug and the adjoining portion of the terminal wire, and a spark plug post terminal receiving means connected to the closed end of the socket and adapted to be locked to the post terminal with the axis of the sleeve at right angles to the axis of the post, whereby the socket will be held against a longitudinal strain tending to disconnect the plug and its terminal wire from the socket.

2. A terminal connector comprising a tubular terminal member adapted to be connected to a terminal wire and a sheet metal

post terminal clip rigidly secured to said terminal member and bent to form two opposed gripping jaws adapted to receive a post terminal between them and forming a longitudinally split resilient sleeve, said terminal clip being rigidly secured to the terminal member on the inner side thereof.

3. A terminal connector comprising a tubular terminal member having a closed outer end, means for detachably and electrically connecting a terminal wire thereto, a terminal clip of sheet metal bent to form two integral opposed gripping jaws adapted to receive the post terminal between them, the connected ends of said jaws being passed through the closed end of the terminal member and expanded within the said member to rigidly secure said jaws to said member.

4. A terminal connector comprising a terminal member, means for detachably and electrically securing a terminal wire thereto, a terminal clip formed of a single piece of sheet metal bent to form two opposed gripping jaws, the inner ends of said jaws being passed through the closed end of the terminal member and expanded therein to rigidly connect the gripping jaws to said member, and integral reinforcing lugs carried by the gripping jaws.

5. A terminal connector comprising a terminal member, means for securing a terminal wire thereto, a terminal clip formed of a single piece of sheet metal bent to form two opposed gripping jaws, the inner ends of said jaws being passed through the closed end of the terminal member and expanded therein to rigidly connect the gripping jaws to said member, and integral reinforcing lugs carried by the gripping jaws, said reinforcing lugs bearing against the terminal member and serving as braces for the gripping jaws.

6. A terminal connector comprising a terminal member, means for securing a terminal wire thereto, a terminal clip formed of a single piece of sheet metal bent to form two opposed gripping jaws, the inner ends of said jaws being passed through one end of the terminal member and expanded therein to rigidly connect the terminal clip to said member, and a pair of integral reinforcing lugs carried by each jaw of the terminal member, said lugs extending outwardly and bearing at their inner ends on the end of the terminal member and serving as braces for the gripping jaws.

In testimony whereof I hereunto affix my signature in the presence of two witnesses.

CHARLES W. BECK.
